(57) **CLAIM**

The ornamental design for an electric heater, as shown and described.

DESCRIPTION

1. Electric heater
2. Electric heater
- 1.1 : Front
- 1.2 : Back
- 1.3 : Left
- 1.4 : Right
- 1.5 : Top
- 1.6 : Bottom
- 1.7 : Perspective
- 2.1 : Front
- 2.2 : Back
- 2.3 : Left
- 2.4 : Right
- 2.5 : Top
- 2.6 : Bottom
- 2.7 : Perspective

The elements contained within the broken lines in images 1.2 and 2.2 constitute disclaimed subject matter that forms no part of the claimed design.
